(57) **CLAIM**

The ornamental design for a toothbrush holder, as shown and described.

DESCRIPTION

FIG. 1 is a top front perspective view of a toothbrush holder, showing our new design.

FIG. 2 is a bottom rear perspective view of the toothbrush holder.

FIG. 3 is a front elevational view of the toothbrush holder.

FIG. 4 is a rear elevational view of the toothbrush holder.

FIG. 5 is a left side elevational view of the toothbrush holder.

FIG. 6 is a right side elevational view of the toothbrush holder.

FIG. 7 is a top plan view of the toothbrush holder; and,

FIG. 8 is a bottom plan view of the toothbrush holder.

The toothbrush holder is shown with symbolic breaks in its width. The appearance of any portion of the article between the break lines forms no part of the claimed design. The broken lines show portions of the toothbrush holder that form no part of the claimed design.

1 Claim, 8 Drawing Sheets
